CLAIM

The ornamental design for a tool holder, as shown and described.

DESCRIPTION

FIG. 1 is a top, front perspective view of a tool holder according to my new design;

FIG. 2 is a bottom, front perspective view thereof;

FIG. 3 is a front elevation view thereof;

FIG. 4 is a rear elevation view thereof;

FIG. 5 is a left side elevation view thereof, the opposite side being a mirror image thereof;

FIG. 6 is a bottom plan view thereof; and,

FIG. 7 is a top plan view thereof.
